WHIPSTOCK

Cecil C. Cutrer and Joseph Leroy Broussard,
Sulphur, La., assignors to George J. Barrett
and Sosthene Robichaux, Houston, Tex.

Application June 4, 1935, Serial No. 24,960

12 Claims. (Cl. 255—1)

This invention relates to drilling apparatus and more particularly to a means for deflecting a hole or straightening a crooked hole in the ground.

5 An object of this invention is to provide a whipstock which is adapted to be secured to an end of the drill and drill stem so that the drill may move past an obstruction in the well which is of such a character that it cannot be withdrawn therefrom.

Another object of this invention is to provide a device of this character which is initially fixed to the drill stem above the drill or bit and which may be released from the drill stem and operate 15 as a guide means therefor in order to permit the drilling of a bi-passage around an obstruction in the well or opening.

A further object of this invention is to provide a whipstock which is so constructed that after the stem of the drill has been released from the whipstock body, the entire body may be turned within the well opening to re-position the body or for any other purpose.

A still further object of this invention is to 25 provide a device of this character which includes a pair of frangible means, one of which is initially adapted to hold the drill stem against rotation within a guide eye and the other of which is to dispose a second guide eye at the lower 30 portion of the whipstock body so that rotation of the drill will not injure the whipstock body.

The above and various other objects and advantages of this invention will in part be described in, and in part be understood from the 35 following detail description of the present preferred embodiment, the same being illustrated in the accompanying drawing, wherein:—

Figure 1 is a detail side elevation partly in section of a device constructed according to an 40 embodiment of this invention.

Figure 2 is a detail front elevation of the device.

Figure 3 is an enlarged sectional view taken on the line 3—3 of Figure 2.

45 Referring to the drawing, wherein like numerals of reference designate corresponding parts throughout the several views, the numeral 10 designates generally an elongated body which tapers longitudinally, being provided at its lower 50 end with a blade or point 13. Preferably, this body 10 is substantially round in transverse section and is provided with a flat face 11 having a T-shaped guide channel 12, extending longitudinally thereof. This guide channel 12 terminates 55 at a point spaced downwardly from the

upper end of the elongated body 10 and a second guide channel 14 of similar construction is disposed in the body 10 and terminates at its lower end at a point spaced upwardly from the upper end of the lower or elongated channel 12 and the upper end of the upper guide channel 14 terminates at a point spaced downwardly from the upper end of the body 10. A slide 15 having a guide eye 16 is slidably disposed in the upper guide channel 14 and is movable longitudinally of the guide channel.

The stem portion 17 of a drill or drill rod loosely extends through the eye 16 of the guide member 15 and initially this stem 17 is fixed relative to the eye 16 by means of a frangible 15 pin 18. This pin 18 may be either driven or threaded into the eye 16 and the stem 17.

A second guide member 19 is slidable in the lower guide channel 12 and is provided with an eye 20 which rotatably receives the stem 17 and the stem 17 at a point closely adjacent the upper edge of the guide eye 20 has a frangible pin 21. As shown in the drawing, the guide channel 12 is inclined to the flat face portion 11 of the body 10 so that in the event the body 10 be 25 disposed in substantially a vertical position in the well opening, the guide member 19—20 will move at an angle to the vertical and thus move the drill bit 22 away from the obstruction in the well. The guide member 19 may have a relatively snug fit in the guide channel 12 so that the eye 20 will not readily slide downwardly when the device is being inserted into a well opening or pipe. In this manner the locking means 30 hereinafter described carried by the eye and the 35 drill will not prevent rotation of the drill stem during the time that the drill is moving downwardly with respect to the body 10.

A collar or sleeve 23 is secured to the stem 17 at a point closely adjacent the upper end of the 40 bit 22 and is provided with teeth or projections 24 on the upper side thereof. These teeth or projections 24 are adapted to engage teeth or projections 25 on the lower side of the guide eye 20 when the device is being withdrawn from the well. As the stem 17 is being pulled upwardly with the body 10 stationary in the well, the toothed sleeve 23 will contact with the toothed eye 20 so that the body 10 will not rotate relative to the stem 17 and so that, if desired, the entire body may be turned relative to the lower portion of the well or that portion adjacent the obstruction.

50 In the use and operation of this device, the 55

body 10 is initially fixedly secured to the stem 17 by inserting the stem 17 through the guide eyes 16 and 20. The upper frangible pin 18 is secured to the eye 16 and the stem 17 so that the eye 16 cannot move relative to the stem 17. The lower frangible pin 21 is secured in the stem 17 adjacent the upper edge of the eye 20. The drill rod with the bit 22 and the body 10 is then inserted in the well opening until the point 13 contacts 10 with the projection. The point 13 will permit the body 10 to initially be inclined relative to the vertical unless the obstruction is such that the body 10 will remain in the vertical position. The weight of the drill rod stem 17 is sufficient to 15 break the pin 18.

At this time the slide 15 will be at the lower-most limit of the guide channel 14. The action of breaking the pin 18 will drive the point of 20 13 tightly into the lower portion of the well so that the body 10 will be tightly engaged within 25 the well opening at the bottom thereof. When the pin 18 is broken, the drill stem 17 may be rotated and the bit 22 moved downwardly along the inclined face 11 of the body 10. The frangible pin 21 will cause the lower guide member 19-20 to move downwardly in the lower elongated guide channel 12 and will keep the bit 22 away from the flat face 11 of the body 10 so that this bit 22 will not cut into the body 10 and thus 30 injure the body, and will also prevent whipping of the bit 22.

When the guide 19-20 is at the bottom of the 35 guide channel 12, further rotation and movement of the stem 13 will break the frangible pin 21 so that the bit 22 on the stem 17 may be moved to the desired depth past the obstruction in the well.

After the bit 22 has been drilled to the desired 40 depth past the obstruction, the bit 22 and the stem 17 may be raised and in this operation, the body 10 will initially be stationary. When the toothed 45 collar 23 engages the guide member 19-20, this guide will move upwardly to the upper end of the guide channel 12. At this time, the rotation of the stem 17 may be stopped and the stem pulled 50 upwardly until the guide 19-20, engages the upper end of the guide channel 12. In the event, the body 10 is driven tightly into the ground so that straight upward movement of the stem 17 will not release the body 10, the stem 17 may be 55 turned or oscillated back and forth with the toothed collar 23 engaging the teeth 25 of the guide eye 20. When the teeth 24 engage the teeth 25, the reciprocation or partial turning in either direction of the stem 17 will effect a similar turning movement to the body 10 so that the body may be readily withdrawn from the well.

It is, of course, understood that various changes and modifications may be made in the details of 60 construction and design of the above specifically described embodiment of this invention without departing from the spirit thereof, such changes and modifications being restricted only by the scope of the following claims.

65 We claim:—

1. A device as set forth comprising a body insertable in a well opening having an inclined longitudinal face on one side and provided with a guide channel, a slide in said channel and a sleeve secured to said slide and loosely engaging about the stem of a drill to hold the drill in spaced relation to the inclined face.

2. In combination with a drill bit and drill stem, an elongated body provided with an inclined face on one side thereof and provided with

a guide channel in said one side, a slide engaging in said channel, an eye secured to said slide, and frangible means holding the eye and the stem against movement relative to each other.

3. In combination with a drill and a drill stem, 5 an elongated body provided with a guide channel disposed at an angle to one face of the body, a slide engaging in said channel, an eye carried by said slide and loosely engaging about the drill stem and a frangible pin holding the eye and the stem against movement relative to each other.

4. In combination with a drill and a drill stem, 15 an elongated body provided with an inclined face on one side thereof and with a guide channel in said one side, a second guide channel alining with 20 said first guide channel, a pair of guides disposed one in each guide channel and frangible means engaging at least one of said guides to hold the drill stem against movement relative to said one guide.

5. A device as set forth comprising a body having a reduced lower end portion, said body having an elongated guide channel terminating at a point spaced downwardly from the upper end thereof, said body also having a second guide 25 channel substantially shorter than the first guide channel and substantially alining with said first guide channel, a pair of slides disposed one in each guide channel and frangible means engageable with one of the guides and with a member 30 extending through the guides to hold the member against movement relative to said one guide.

6. A device as set forth comprising an elongated body provided with a longitudinally extending 35 guide channel terminating at a point spaced downwardly from the upper end of the body, a second guide channel substantially alining with the first guide channel and extending upwardly 40 therefrom, a pair of slides disposed one in each guide channel and a pair of drill stem engaging eyes carried one by each guide.

7. In combination with a drill bit and a drill stem, an elongated body provided with a longitudinally extending guide channel and a second 45 guide channel substantially alining with the first guide channel, a pair of slides disposed one in each guide channel, an eye carried by each slide and loosely engaging about the drill stem, a frangible pin secured to one of said eyes and engaging the drill stem to hold the drill stem against rotation relative to said one eye and a second 50 frangible pin secured to the drill stem whereby said other guide member will move downwardly in the guide channel upon movement of the stem 55 incident to the rotation thereof.

8. In combination with a drill bit and a drill stem, an elongated body provided with a lower elongated guide channel and an upper relatively short guide channel, a pair of slides disposed one 60 in each guide channel, an eye carried by each slide and loosely engaging about the drill stem, a frangible pin engaging the upper eye and also engaging the drill stem to initially hold the drill stem against rotation and longitudinal movement 65 relative to said upper eye, a second frangible pin secured to the drill stem above the other eye whereby rotation of the drill stem coactive with longitudinal movement thereof relative to the body will move the other guide longitudinally of 70 its guide channel and coacting means carried by the drill stem and the lower eye to effect rotation of the eye and the body when the drill stem is being withdrawn from the well opening.

9. A device as set forth comprising an elong- 75

gated body provided with an inclined face on one side thereof and with a guide channel in said one side, a slide engaging in said channel, an eye secured to the slide and frangible means engageable with the eye and with a drill stem disposed in the eye to hold the eye against movement relative to the stem.

10. In combination, a whipstock having a deflecting face, a carriage movable longitudinally along said face and a boring tool rotatable on the carriage, said carriage being arranged to hold the tool out of contact with said face as the tool rotates.

11. In combination, a whipstock having a deflecting face formed with a track, a stop at the upper end of the track, a tool carriage connected to and mounted to move along the track, a boring tool rotatable on the carriage and engageable therewith upon upward movement of the tool to

move the carriage upwardly into engagement with the stop whereby, upon further upward movement of the tool the whipstock and tool are simultaneously removed from the well.

12. In combination, a whipstock shaped to be lowered into a well and having a deflecting face formed with a track and having a stop at its lower end, a tool carriage movable along the track, a boring tool rotatable on the carriage, said carriage being arranged to hold the tool out of contact with said face as the tool rotates and moves downwardly, said stop being arranged to arrest the downward movement of the carriage, the tool being mounted to move further downwardly, relative to the carriage upon the arrest of such downward movement of the carriage.
